[57] CLAIM

The ornamental design for a leaf bag holder, as shown.

DESCRIPTION

FIG. 1 is a perspective view on a reduced scale of a leaf bag holder, showing my new design;

FIG. 2 is an enlarged side elevational view thereof;

FIG. 3 is a rear elevational view thereof with portions broken away;

FIG. 4 is a bottom plan view;

FIG. 5 is an enlarged section taken on the line 5—5 of FIG. 1.
